[57] CLAIM

The ornamental design for an ottoman, as shown and described.

DESCRIPTION

FIG. 1 is a perspective view of an ottoman showing my new design;

FIG. 2 is a front elevation view thereof, the rear elevation being a mirror image of the side shown;

FIG. 3 is an end elevation view thereof, the opposite end being a mirror image of the side shown; and,

FIG. 4 is a top plan view thereof.
